I claim the ornamental design for an automobile wheel, as shown and described.

DESCRIPTION

FIG. 1 is a front elevational view of an automobile wheel with five spokes;

FIG. 2 is a perspective view thereof;

FIG. 3 is a front elevational-view of an alternative embodiment of an automobile wheel with six spokes; and,

FIG. 4 is a perspective view thereof.

The broken lines in the drawings of the automobile wheel are for showing portions of the automobile wheel and form no part of the claimed design.
